UNITED STATES PATENT OFFICE

HENRY HEITLAGE, OF ST. BERNARD, OHIO, ASSIGNOR TO THE PROCTER & GAMBLE COMPANY, OF CINCINNATI, OHIO, A CORPORATION OF OHIO

CAN

Application filed February 2, 1929. Serial No. 337,070.

My invention relates to a novel modification of the type of can which has a weakened tearing strip adjacent an end thereof which may be removed by a key which is secured to 5 a projecting portion secured to the tearing strip, and which, by rotation, winds up the tearing strip in a coil, so that the end of the can becomes detached, thereby providing an opening for the can.

10 It is the object of my invention to provide a can which may be provided with a tearing strip in a single ply band at its upper end which, when torn away, will crimp outwardly the edge of a treble fold of metal adjacent the lower edge of the tear strip and thus leave a smooth peripheral edge of suitable rigidity to retain a push lid which, with the removal of the tearing strip, is detached from the body of the can. It is further my 15 object to form the can body from an integral sheet of tin which is so folded that a three-fold reinforcing band is provided below the top wall which lies adjacent the lower peripheral edge of the tearing strip. It is further my object to provide a multiple lap seam which will form a closure in which inner and outer plies of the metal are in other than simple overlapping relation with an intermediate ply forming a butt joint, as I have found 20 that such a construction presents difficulties from the point of view of forming and soldering the side joint. It is my object to form a joint in which the inner layer of metal is overlapped by at least three outer layers thereby 25 forming a stronger joint than in a construction in which there are only two overlapping layers.

Another specific object of my invention is to provide a can having a tearing strip, the 30 upper edge of which will lie adjacent a bead or double seam formed by the attachment of the can body and lid so that when the strip is removed there will be a smooth non-jagged edge formed on the lid.

40 The above and other objects to which reference will be made in the ensuing disclosure I accomplish by that certain combination and arrangement of parts of which I have shown a preferred embodiment.

45 Referring to the drawings:

Figure 1 shows a plan view of one type, a blank for my novel can body in which the lap seam is formed with three overlapping layers.

Figure 2 is a plan view of the blank shown in Figure 1 after the lap seam and reinforcing band have been folded over. 55

Figure 3 is a side elevation of the can formed from the blank shown in Figures 1 and 2 with a cut away portion showing the construction at the lap seam. 60

Figure 4 is a detail sectional view taken along the lines 4—4 in Figure 3.

Figure 5 is a plan view of a different type of blank formed for making a lap seam joint formed with an inner overlapping joint with 65 intermediate and outer layers butt jointed.

Figure 6 is a plan view of the blank shown in Figure 5 after the lap seam and reinforcing band have been folded over. 70

Figure 7 is a side elevation of the can formed from the blanks shown in Figures 5 and 6 with a cut away portion showing the structure at the lap seam. 75

Figure 8 is a detail sectional view taken along the lines 8—8 in Figure 7. 75

Figure 9 is a plan view of a still further modified type of blank for forming a can with a lap seam consisting of inner and intermediate layers overlapping and the outer layer terminating at a butt joint. 80

Figure 10 is a plan view of the blank shown in Figure 9 after folding over the locking strips and reinforcing band.

Figure 11 is a side elevation of a can formed from the blank shown in Figures 9 and 10 85 with cut away portions showing the structure at the lap seam.

Figure 12 is a detail sectional view taken along the lines 12—12 in Figure 11.

The body of the can is formed of a blank 90 of metal such as tin having a top edge 1, bottom edge 2, and meeting edges 3 and 4, which for the greater portion of the can have a lock seam joint formed by bending over the edges 3 and 4 along the lines 3^a, 4^a. A band of metal 5 at the top provides a crimping band for securing the lid of the can to the body. The lid 6 is a usual construction having an annular depressed portion 7 within which a key may be attached in a suitable manner. 100

Below and immediately adjacent the crimping band 5, the tearing strip 8 is disposed. While I have shown a herringbone type of tearing strip, the tear strip may also be formed by a double score line.

5 The tearing strip has a tongue 9 which, when the can body is formed, provides means for attachment by the key which, in the usual construction, has a slot which engages the 10 protruding tongue 9, and by the rotation of the key removes the tearing strip.

10 The metal of the can wall above and below the tear strip is notched out as indicated at 10 to facilitate the starting of the tear strip.

15 The metal of the can wall below the tearing strip is folded over to make a three ply reinforcing band. In Figures 1, 5 and 9, the area comprising the outer layer of the three ply fold is indicated by dotted lines $a-a$. The 20 intermediate layer is indicated by the lines $b-b$ and the inner layer is indicated by the lines $c-c$.

25 The portion 3 may be bent outwardly along the line 3^a and the portion 4 may be bent inwardly along the line 4^a to form hooks which provide the joint of the can wall. Solder may be applied to this lapped joint. At the juncture of the meeting edges of the reinforcing band, unless the metal were cut away, 30 the triple fold of the reinforcing band would form a six ply layer. In order to avoid a six ply layer which would be difficult to solder and at the same time avoiding a butt joint in the intermediate layer with overlapping 35 joints on the inner and outer layer which makes a four ply layer with only two overlapping joints, I cut away the metal at the edges of the part of the can which is to be trebly folded, as illustrated in the several 40 modifications.

45 In the modifications shown in Figures 1 to 4, the portion to form the reinforcing band has staggered extensions a^1 , b^1 and c^1 at one edge and staggered cut away portions a^2 , b^2 , c^2 at the other edge so that when the can is lock seamed, there will be formed in the reinforcing band joint, an overlapping joint between the inner layers of the fold, lapped joints between the intermediate layers and 50 at least three overlapping joints between the combined layers. It is also significant of this modification that the innermost end laps the next two ends which form a butt joint, the next two ends also form a second butt joint. 55 The first butt joint and the second butt joint are offset to form an intermediate lap and the outermost layer laps the last butt joint to form a third lap.

60 In the modifications shown in Figures 5-8, there is only one extension C^1 of the area $c-c$. When the can is lock seamed, there will be formed in the reinforcing band an inner layer having a lapped joint and intermediate and outer layers having butt joints. 65 It is significant of this joint that the inner-

most end overlaps the next two ends which form a butt joint. This butt joint lies parallel to a butt joint formed between the meeting ends of outer layers and the remaining end terminates at the junction point of the 70 two previous butt joints.

In the modifications shown in Figures 9-11, the edges of the area $a-a$, $b-b$, and $c-c$ are extended in a staggered arrangement at one side of the blank as indicated at 75 a^1 , b^1 , and c^1 , while at the other edge only the area $c-c$ is cut away as indicated at c^2 . The joint formed by this modification consists of two lap joints and two butt joints. Also it is significant of this type of joint that the 80 innermost end overlaps the next two ends which form a butt joint. The next two ends toward the outer side of the can abut and the latter ends overlap the first butt joint. The remaining end terminates at the junction of 85 the ends which form the latter butt joint.

Thus at the joint in all these modifications, 90 there is a four ply layer with three laps and in each the inner layers form a lapped joint which forms a seat for the solder. Each modification has at least two butt joints 95 which permit the ingress of solder so that there will be no tendency for the can to leak.

After cutting out the blank the portions 3 and 4 are first bent one inwardly and the 95 other outwardly and then hooked together. The lateral edge joint formed accordingly is then pressed to form a lock seam. The edge portions of the three ply reinforcing band slip naturally into place during the formation of the lock seam. Solder is then applied to the lock seam and the overlapping upper 100 portions 12 and lower portions 13 of the can body are also secured with this same soldering operation. The lid and bottom of the 105 can are applied by crimping in the usual manner.

The can made in accordance with the foregoing description is usually economical in 110 the amount of tin required. The operation of removing the tearing strip leaves smooth, non-jagged edges so that there is no likelihood of a woman cutting her hands either during the removal of the tearing strip or in the use of the can after the strip has been 115 removed. The lid will further fit snugly in the opening formed after the lid has been removed. The operation of removing the tearing strip also completely releases the lid. This is considered an advantage as the lids of some cans of this type have a tendency to 120 stick at the soldered joint, which prevents the ready removal thereof.

Having thus described my invention, what I claim as new and desire to secure by Letters 125 Patent, is:—

1. A blank for a can with a tearing strip, the removal of which releases the lid, comprising a blank from which the can body is formed, said blank having a band at one 130

edge for crimping to retain the can lid, a band, one edge of which lies immediately adjacent said crimping band weakened to provide a tearing strip, and a band, one edge of which lies adjacent the opposite edge of said tearing strip for providing a bent reinforcing band of three layers and the meeting edges of the portion for forming the reinforcing band shaped so as to form a four ply layer with three overlapping joints and at least two butt joints.

2. A can having a body portion with a band at one edge crimped to the can lid, a weakened tearing strip lying adjacent said crimped band, and a portion adjacent said tearing strip folded in a triple layer, the portion folded in a triple layer so disposed that the removal of the tearing strip will bend the torn edge of the can body against the middle of said layers.

20 3. A can having a body with a tearing strip, and a portion adjacent said tearing strip folded in a triple layer, the portion folded in a triple layer so disposed that the removal of the tearing strip will bend the torn edge of the can body against the middle of said layers.

30 4. A can having a body with a tearing strip, and a portion adjacent said tearing strip folded in a triple layer, said portion of the body having a lateral joint in which the four ply layers are soldered in triple overlapping relation with at least two butt joints.

35 5. In a can of the character specified, a plurality of layers forming a reinforcing band, and a tearing strip so disposed with relation to said reinforcing band that the lower line of fracture of said tearing strip will be adjacent the inner of said plurality of layers.

40 6. A can having a reinforcing band consisting of a plurality of layers of the can body, said can having a tearing strip an edge of which lies adjacent the inner of said plural layers.

45 7. In a can of the character specified, a plurality of layers forming a reinforcing band, and a tearing strip so disposed with relation to said reinforcing band that the lower line of fracture of said tearing strip will be adjacent the inner of said plurality of layers, and said plural layers trebly overlapped at the lateral edge joint.

50 8. In a can of the character specified, a plurality of layers forming a reinforcing band, and a tearing strip so disposed with relation to said reinforcing band that the lower line of fracture of said tearing strip will be adjacent the inner of said plurality of layers, and said plural layers trebly overlapped at the lateral edge joint and having at least two butt joints.

HENRY HEITLAGE.
